POWER TAKE-OFF DEVICE

Henry D. Breen, Chicago, and Adolph G. Kuellmar, Blue Island, Ill., assignors to Union Asbestos & Rubber Company, Chicago, Ill., a corporation of Illinois

Application January 17, 1947, Serial No. 722,534

7 Claims. (Cl. 105—131)

1

The invention relates to a power take-off of the type used on railway cars for actuating fans and like accessories and, more particularly, to a take-off device on a refrigerator car in which the power is taken off of the periphery of the car wheel and a flexible drive shaft is used.

An important object is the provision of a take-off device wherein the take-off roller will follow the movement of the car wheel when the car is operated on curved track, and wherein the take-off roller will selectively operatively engage the car wheel during this movement.

A further object of the invention is to provide means for selectively disengaging the take-off roller from the car wheel.

An important object of the invention is to provide new and novel means for swingably mounting the take-off roller whereby the associated flexible drive shaft will not be bent on a radius smaller than the predetermined minimum radius for eliminating stress and breakage of the flexible shaft.

Another object is to provide a mounting for the take-off roller which will protect the flexible drive shaft from attrition due to flying road ballast and other like particles.

A further important object is to provide a new and novel take-off device wherein the take-off roller is always within the plane of the car wheel, eliminating the necessity for the use of auxiliary means to support the roller in its off-the-wheel positions.

Another object is to provide a simple take-off device of few parts which may be manufactured, installed and maintained in operative position at low cost.

A further object is to provide new and novel means for bending the flexible shaft portion below the car body on a true radius throughout its length, during all service movements of the car wheel with respect to the car body.

In the drawings, in which like reference characters refer to like parts:

Fig. 1 is a fragmentary sectional view through a car embodying the invention; the section being taken along line 1—1 of Fig. 2.

Fig. 2 is a fragmentary side elevational view of the portion of the car structure shown in Fig. 1.

Fig. 3 is a diagrammatic drawing illustrating the normal service positions of the car wheel and cooperating take-off roller of the present invention.

Fig. 4 is a diagrammatic drawing illustrating the normal service positions of the car wheel and cooperating take-off roller of the flexible-shaft

2

take-off structures of the Pilley and Moorman patents hereinafter referred to.

Fig. 5 is a diagrammatic plan view illustrating the normal service positions of the car wheels with respect to the body of a car and showing the service positions of the take-off roller of the present invention with respect to the various positions of the cooperating car wheel.

Fig. 6 is a side elevational view of the cooperating car wheel and take-off roller of Fig. 5.

Throughout the following specification, the word "inner" is intended to mean toward the longitudinal center of the car and the word "outer" is intended to mean toward the side wall of the car.

In the drawings, a car floor 10 and side wall 12 are shown in supported relation with a center-sill 14. A side-sill 16 and spaced intermediate sills may form a part of the car body supporting structure. The car body may be pivotally mounted upon the usual car trucks which include car wheels 20 and truck side frames 22. The foregoing structure is conventional car design.

A substantially U-shaped trough-like member 24 may be horizontally disposed intermediate the center-sill 14 and the car wheel 20 and may be pivoted adjacent its inner, upper side walls to spaced butt members 26 affixed preferably to the upper portion of the center sill by pivot pins. A

30 strap-like U-shaped yoke 28 may be coaxially pivoted adjacent its opposed end portions to the butt members 26, by the same pivot pins, and may be disposed in outwardly spaced and generally underlying relation with the inner margin of the member 24. A flexible drive shaft 30 may be co-operatively connected to a fan or other accessory in the body of the car and may extend substantially vertically through the car floor and may be arcuately bent about a relatively large radius in

35 nested relation with the trough-like member 24, terminating in a substantially horizontal outer end portion journaled in a bearing member 31 secured in nested relation with the outer end portion of the trough-like member 24 by an overlying clamp member 32 or other suitable removable clamping means.

A take-off roller 34 may be operatively secured to the outer end of the shaft 30 in substantially coplanar overlying relation with the car wheel 20. A lever 36 may be secured adjacent its inner end to one of the upwardly extending portions of the yoke 28, terminating at its outer end in a handle portion adjacent the side-sill 16. A brace member 38 may be affixed adjacent one end

50 thereof to the periphery of the yoke 28 and may

extend obliquely toward and be affixed adjacent its opposed end to the lever 36 for the purpose of rigidizing the relation of the lever with the yoke. A tubular housing 40 may be disposed in a substantially horizontal plane in adjacent spaced relation with the member 24, intermediate the member 24 and the brace member 38. The outer end portion of the housing 40 may be formed with a mounting bracket 42 adapted to be pivotally secured to a cooperating bracket 44 on the adjacent wall portion of the member 24. A horizontally disposed pivot pin 46 may extend through abutting portions of the brackets 42 and 44 adapted to permit the housing 40 to swing in a vertical plane about the pivotal pin 46. The inner end portion of the housing may be formed with an end wall 48 having a central aperture therethrough. A rod 50 may be pivotally secured to the yoke 28 at its inner end and may extend through the aperture in the end wall 48 with its major outer end portion axially disposed within the housing 40 and provided adjacent its outer end portion with a washer 52 in peripheral sliding relation with the bore of the housing. The outer end of the rod 50 may be threaded and provided with one or more nuts, adapted to limit the movement of the washer 52 in one direction lengthwise of the rod 50. A spring 54 may be disposed within the housing intermediate the end wall 48 and the washer 52, for purposes hereinafter described.

A bracket 56 may be secured to the side-sill 16 and may be formed with a vertically disposed elongated aperture 58 terminating in upper and lower offset portions 60; this bracket being adapted to guide the handle portion of the lever 36 for vertical movement within the aperture 58. The opposed adjacent portions of the offset portions 60 may be formed with vertically disposed lugs 62 adapted to maintain the lever 36 against lateral movement in both its upper and lower positions. If desired, the bracket 56 may be formed with suitable locking means adapted to cooperate with and lock the lever 36 in its raised and lowered positions. A bracket 64 may be secured to one of the intermediate sills for the purpose of mounting an auxiliary motor or other driving means, for actuating the drive shaft 30 when the car is not in motion, as at a loading or unloading platform. The bracket 64 may be formed with holes or other suitable attachment fixtures to register with the attachment means on the auxiliary motor. The take-off roller 34 may be provided with an axially disposed projecting threaded portion 66 adapted to be fitted with a pulley (not shown) adapted to be connected by belt means with the auxiliary motor.

It is particularly pointed out that the principal object of the invention is to provide a flexible shaft driving means for a fan or other like accessory, wherein the take-off roller is driven from the periphery of the car wheel and wherein the flexible shaft will not be bent on a radius small enough to damage or fracture the flexible shaft, during movement of the car on tracks of short radius curves.

The prior art shows flexible drive shafts for actuating a fan in refrigerator cars; the drive shafts being actuated by a power take-off roller engageable with the tread of the car wheel. Some of these prior art structures showed the take-off roller mounted upon the car body, in overlying relation with the tread of the car wheel, while others showed the roller mounted upon

the car trucks. Where the take-off rollers were mounted upon the car body, difficulty was encountered in keeping the roller in contact with the car wheel tread, due to the fact that the car wheel has a wide range of movement, with respect to the car body, when the car is on curved track. Where the take-off rollers were mounted upon the car trucks, the roller would maintain a fixed driving relation with the tread of the car wheel, but the wide range of movement of the car wheel and cooperating roller (with respect to the car body) resulted in bending the flexible drive shaft about a radius smaller than the critical (safe) bending radius of the flexible shaft, when the car was on curved track, resulting in fatigue and breakage of the shaft. The present invention is adapted to provide a flexible drive shaft and cooperating take-off roller wherein the latter will maintain driven contact with the tread of a car wheel when the car is on curved track and wherein the roller-mounted end portion of the shaft is so mounted on the car body that the flexible shaft will never be bent about a radius small enough to adversely affect the shaft.

One of the most important objects of the present invention is that of mounting the bendable portions of the flexible shaft in a manner wherein the roller may follow the tread of the car wheel, when the car is on curved track and insure against the bending of the flexible shaft about a radius small enough to damage the shaft. It is particularly pointed out that the wide range of movement of the roller-driving car wheel, with respect to car body, is considerable and this range of movement is accurately illustrated in Figs. 3 to 6, inclusive, of the accompanying drawings.

It will be understood from the drawings that the take-off roller of the present invention moves in an arc concentric with the pivot about which the member 24 swings during movement of the car wheel with respect to the car body. It will be understood from the drawings that the take-off roller of the present invention has substantially its full width within the plane of the car wheel during all service movements of the car wheel with respect to the car body, for which reason no auxiliary fittings are required to support the roller in an off-the-wheel position.

To place the power take-off of the present invention in position for actuating the flexible drive shaft and the associated car accessory, the lever 36 may be placed in the lower offset portion 60 of the bracket 56, as shown in Figs. 1 and 2. The lever will be held in this position by the lug 62 and the action of the spring 54; the latter urging the lever in an upward direction. With the lever in the position last described, the take-off roller will be held in driven engagement with the car wheel by the action of the spring which urges the outer end of the member 24 in a downward direction. It will be seen that the tension in the spring may be suitably adjusted by manipulating the nuts on the outer end of the rod 50. To move the take-off roller out of driven engagement with the car wheel, the lever may be raised into interlocked relation with the upper offset portion of the bracket 56 where it may be maintained by gravity. The vertical portion of the flexible drive shaft adjacent the upper plane of the car floor may be held in clamped relation with the car floor by a suitable member 68 and a cavity 70 may be formed within the upper and lower planes of the car floor, coincident the flexible drive shaft,

adapted to permit movement of the drive shaft laterally of the car.

The cavity 70 is adapted to permit the flexible shaft to bend arcuately adjacent the upper plane of the car floor in order to bend the shaft about a relatively large radius and this cavity may be filled with a resilient packing (not shown) adapted to permit movement of the shaft and provide an insulating member occupying the cavity.

It will be noted that the axis of the take-off roller is coaxial with the longitudinal axis of the mounting member 24 and that the take-off roller is subject to side thrusts as it is moved vertically by the periphery of the car wheel, for which reason we prefer to pivotally secure the mounting member to the car by a pair of pivot pins spaced with respect to each other in order to provide the necessary longitudinal rigidity in the mounting member to resist these side thrusts and limit the service movements of the take-off roller to a vertical plane.

Viewing Fig. 3 of the drawings, it will be seen that the take-off roller moves in a vertical plane throughout an arc concentric with the pivot point of the mounting member, enabling the take-off roller to follow the tread of the car wheel during the service movements of the latter. We feel that it is important that the last mentioned pivot point be as close to the center sill and the car floor as possible in order to preserve a maximum radii in the arcuately bent flexible shaft.

Fig. 3 of the drawings shows diagrammatically a sectional view, taken along line 3-3 of Fig. 6, to illustrate the relative service positions of a car wheel of a conventional railway car when the latter is on straight and curved track. Positions A and C indicate the extreme service positions of the car wheel on curved track of shortest conventional radii, and position B indicates the car wheel on straight track. Fig. 3 also shows the take-off roller and associated flexible shaft of the present invention in their relative operative positions with respect to the car wheel when the latter is in positions A, B and C. Fig. 3 shows the radii of the arcuately bent flexible shaft of the present invention in all of its service positions.

Fig. 4 of the drawings is identical with Fig. 3 with the exception of the take-off roller and associated flexible shaft, for the purpose of comparing the prior art structures with the present invention, particularly with respect to the service positions of the take-off roller and its relation with the car wheel in the prior art structures and the critical bending of the flexible shaft of the prior art structures in service movements. Fig. 4 shows the radii of the arcuately bent flexible shaft of the prior art structures in service movements.

A flexible shaft of a diameter suitable for driving a refrigerator car fan may be bent on a radius (minimum) of 12 inches, for occasional bends, according to manufacturer's standard recommendations. For continuous rotation of the shaft the critical minimum radius is 16 inches, according to the same recommendations. Viewing Fig. 4, it will be seen that the flexible shaft of the prior art structures is bent on an 8 inch radius when the car wheel is in position A; a radius which the manufacturer advises will cause the flexible shaft to break. It will further be seen, from Fig. 4, that the flexible shaft of the prior art structures does not have sufficient length to permit the associated take-off roller to

assume the position shown in the lowest dotted position, without causing an acute bend at point D shown in Fig. 4 and without putting acute tension on the flexible shaft. It is as important to the proper use of flexible shafting to prevent tension therein as it is to avoid bending the shafting on radii smaller than that recommended by the manufacturer of the shafting; this recommendation being based upon engineering standards and practical considerations. The conditions illustrated in Fig. 4 are common with the flexible shaft take-off devices of the prior art wherein the take-off roller is mounted for movement vertically in a single plane longitudinally with respect to the car and it is these conditions which are responsible for breakage of the flexible shafting and the resultant inoperativeness of the fan or other auxiliary device in the car. It is an important object of the present invention to provide a flexible shaft take-off device wherein these objectionable and fatal features of the prior art structures are eliminated. It will be seen, viewing Fig. 4, that the take-off roller is almost out of engagement with the car wheel when the latter is in position A and is entirely out of engagement with the car wheel when the latter is in position C. It will also be seen, viewing Fig. 3 that the take-off roller of the present invention has its entire width in overlapping relation with the thickness of the car wheel in all of the service positions of the car wheel, and that the flexible shaft of the present invention is bent on a substantially true radii throughout its bent length in all of the service positions of the take-off device.

The foregoing detailed description is given for purposes of illustration and the invention is not to be limited thereby, reference being had to the appended claims for the scope of the invention.

We claim:

1. In a take-off device for a railway car including a take-off roller drivably engageable with a car wheel; a rigid lever pivotally secured at its inner end to the car body adjacent the longitudinal center thereof and swingable in a vertical plane transversely of the car, the take-off roller being rotatably secured to the outer end of said lever and a flexible shaft connected at one end to the roller and curving in a vertical plane with its other end extending vertically through the car floor adjacent the longitudinal center thereof.
2. In a take-off device for a railway car including a take-off roller adapted to engage a car wheel; a horizontally disposed elongated U-shaped plate member pivotally secured adjacent its inner end to the car center-sill swingable in a vertical plane transversely of the car, said roller being rotatably mounted on said member adjacent the outer end of said member and a flexible shaft connected at one end to the roller and curving in a vertical plane with its other end extending vertically upward adjacent the car center sill.
3. The structure of claim 2, wherein the flexible shaft is arcuately formed intermediate its outer end and wherein the lower arcuate portion of the flexible shaft is in overlying nested relation with the plate member which is adapted to protect said lower arcuate portion from attrition caused by flying particles.
4. In a take-off device for a railway car including a take-off roller adapted to engage a car wheel; an elongated member pivotally secured adjacent its inner end to the car and swingable in a vertical plane transversely of the car, said

7
roller being rotatably mounted adjacent the outer end of said member and drivably connected with an auxiliary mechanism by a flexible shaft, a U-shaped yoke normally in underlying spaced relation with said member pivotally secured adjacent its upper ends to the car, a lever rigidly affixed to one of said upper ends terminating in a handle portion adjacent the side sill of the car adapted to be selectively raised or lowered to disengage or permit engagement of said roller with said 10 wheel, respectively, said yoke being adapted to engage and lift said member and its associated roller out of engagement with said wheel when said lever is moved to raised position.

5. The structure of claim 4, wherein spring means is provided intermediate said member and said yoke adapted to yieldably urge said member and its associated roller toward said car wheel when said lever is in lowered position.

6. The structure of claim 4, wherein the handle portion of the lever is adapted for guided vertical movement with a bracket secured to the car adjacent the side sill, said bracket being formed with a vertical slot and upper and lower offset slot portions adapted to maintain the lever in 20 25 selective raised or lowered positions.

7. In a take-off device for a railway car including a center sill, a floor and a take-off roller

5
adapted to engage a car wheel; a member pivotally secured adjacent its inner margin to the center sill swingable in a vertical plane transversely of the car, the take-off roller being rotatably secured to the outer margin of said member and a flexible shaft connected at one end to the roller and curving in a vertical plane with its other end extending vertically upward adjacent the center sill.
